UNITED STATES PATENT OFFICE.

HENRY B. NEWHALL, JR., OF PLAINFIELD, NEW JERSEY.

CONCRETE-INSERT.

1,197,052.

Specification of Letters Patent. Patented Sept. 5, 1916.

Application filed February 1, 1915. Serial No. 5,427.

To all whom it may concern:

Be it known that I, HENRY B. NEWHALL, Jr., a citizen of the United States of America, and residing at Plainfield, in the county of 5 Union and State of New Jersey, have invented new and useful Improvements in Concrete-Inserts, of which the following is a specification.

The main object of my invention is to 10 construct a simple, reliable device of this character which can be readily installed and which will have a considerable range of adjustment and adaptability.

The invention accordingly consists in 15 making the body or insert proper with supporting ledges spaced widely enough apart to permit the passage of the head of the fixture supporting member or bolt therebetween and in supporting the bolt by means of a 20 bridging member constructed so as to permit of its being inserted up between the ledges into a position where it bridges the ledges and lies beneath the head of the bolt. The so-called bridging member is in the nature 25 of a washer, of a length sufficient to bridge the supporting ledges and provided with a bolt-receiving opening therein enough larger than the shank of the bolt to permit said member being shifted into the sustaining 30 position beneath the head of the bolt. The form of the enlarged bolt-receiving opening may vary, but usually it will be made in the form of an elongated slot. This, in addition to providing for the installation of the 35 bridging member beneath the bolt head provides for a considerable lateral adjustment of the bolt on the bridging member. The bridging member is preferably itself adjustable in the insert body, as by being longitudinally or rotatably shiftable therein, depending upon the form of the insert, which may be of rectangular, circular or other desired shape, and means, such as corresponding corrugations or teeth on the meeting 40 faces of the supporting ledges and bridging member, are preferably provided for holding the bridging member in the position to which it is adjusted.

Another special feature of the invention 50 is the provision of a flange or flanges on the top of the bridging member for holding the head of the fixture-supporting bolt against turning irrespective of the lateral adjustment of the bolt head on the bridging member. The confining flange or flanges also

reinforce the bridging member, a feature of considerable importance.

Various other objects and features of the invention will appear as the specification proceeds.

In the accompanying drawings I have 45 illustrated several preferred embodiments of the invention but it will be understood that various changes and modifications may be made without departing from the true spirit 50 and scope of the invention. It will also be understood that the terms employed herein are terms of description rather than of limitation except as may be required by the prior art.

Figure 1, is an end view of an embodiment of the invention, parts being broken away to better disclose the construction. Fig. 2, is a side elevation of the same, also partly broken away. Fig. 3, is a plan view with 75 parts broken away. Fig. 4, is a cross sectional view showing the insert embedded in a wall and illustrating by dotted and full lines how the bridging member or support is inserted up between the ledges into supporting position beneath the upraised head of the bolt or fixture-sustaining element. Fig. 5, is a view on the order of Fig. 4 illustrating a modification wherein the bridging member or washer is reinforced by a second 80 bridging member. Fig. 5^a is a view from beneath, showing the bridging members of Fig. 5 with the bolt shank in cross section. Fig. 6, is a horizontal sectional view of a modified form of the invention, the body 90 here being of the cylindrical type. Fig. 7, is a vertical sectional view of another modification. Fig. 8, is a horizontal sectional view taken substantially on the plane of the line 8, 8 of Fig. 7, a part of the supporting 95 washer being broken away to show parts beneath the same.

The hollow body or base of the insert which sustains the weight and which may be termed the "bearing member" is designated 11. This member is embedded in the material 12 of the ceiling, wall or other structural element, usually with its face flush with the surface 13 of the wall. The bearing member is provided with oppositely disposed supporting ledges 15 located at the base of the chamber 16 in said member. These spaced apart supporting ledges provide an entranceway 17 into the chamber and they are spaced widely enough apart to 110

admit the head 18 of the bolt or fixture-supporting element 19.

The bolt or fixture-supporting element is sustained in the bearing member by a bridging member in the form of a plate or washer 20 which bridges the supporting ledges and lies beneath the head 18 of the fixture support 19. The bridging member is formed with an enlarged bolt-receiving opening therein shown in the first form disclosed as a slot 21 slightly wider than the diameter or thickness of the bolt or fixture support and extending from one edge portion inward to a point usually considerably beyond the center of the member. I propose in fact to extend this slot substantially as far as the edge of the far supporting ledge, substantially as indicated in Figs. 1 and 3 to allow for the bolt being adjusted laterally the full width of the entrance slot 17. The bridging member is preferably provided with parallel upstanding flanges 22 disposed at opposite sides of and substantially parallel to the slot therein and spaced widely enough apart to receive the head of the bolt therebetween. In some cases only a single one of these flanges may be provided.

In using the invention the "insert" proper or bearing member is suitably embedded in the concrete, ordinarily by simply fastening it in proper position on the mold form before the concrete is poured, it being shown as having for that purpose lugs 23 to receive nails for positioning it on the form. Firm anchorage of the bearing member in the concrete is insured usually by providing it with outstanding anchorage lugs or wings 26. In assembling, the fixture support, usually a screw bolt, but whose form may vary to suit different fixtures, is first engaged in the bearing member by inserting the head 18 thereof up through the slot 17 between the ledges into the chamber 16 above the ledges. The support or bridging member 20 is then engaged over the bolt shank and tipped at an angle, as indicated in dotted lines in Fig. 4, such that its upper end will pass up between one ledge and the bolt, the bolt being usually crowded over against the other ledge as shown to provide as much space as possible for the passage of the member. When the bridging member has been pushed up far enough into the chamber for its lower edge to clear the adjacent ledge, as in the full lines, Fig. 4, the member can be slid over, and will ordinarily of its own weight, slide over, into position bridging the two ledges. The head of the bolt or fixture-support will now rest upon and be supported by the bridging member between the confining flanges 22, substantially as indicated in Figs. 1, 2 and 3 and it may be adjusted laterally thereon. The upstanding flange or flanges hold the head of the fixture

support against turning but do not interfere with the lateral adjustment thereof. The flange or flanges furthermore reinforce and strengthen the bridging member.

In addition to permitting the described assemblage of the parts, the slot in the bearing member in the construction shown allows for lateral adjustment of the bolt to the extent of the full width of the slot 17 between the ledges. Furthermore in this first form illustrated the bolt can be set at any position in the full length of the bearing member by simply sliding the support along the ledges to the point desired. For the purpose of retaining the support and bolt in such longitudinally adjusted relation, I may provide the meeting faces of the ledges and the support, that is, the upper surfaces of the ledges and the under surfaces of the support with inter-meshing teeth or corrugations as indicated at 35.

When the fixture support is as illustrated in the form of a screw bolt, either the enlarged integral portion or the nut of the bolt may be engaged with the bridging member, depending upon which end of the bolt it is desired to have exposed. In the latter instance, the nut would be considered as the head of the bolt and treated as such in assembling the parts in the manner previously described.

In the construction illustrated in Figs. 5 and 5^a, a compound bridging member is provided, consisting of a main support 40, which bridges the ledges and a second support 41 which rests upon the first support and provides a seat for the bolt head. Both these supports are in the form of washers, with bolt-receiving openings 42, made sufficiently large to permit them to be tilted far enough to pass up between the ledges and into supporting position beneath the bolt head. In this case it will be noted that the openings 42 are larger than the cross section of the bolt, and, therefore, permit of adjustment. The openings, therefore, may be considered elongated relative to the cross section of the bolt.

In Figs. 6, 7 and 8 I have indicated how the form of the insert and the bridging member may be varied to suit different requirements. In Fig. 6 the bearing member 50 is cylindrical in form, instead of the elongated shape shown in Fig. 3 and the parts of the supporting ledges 15 effective at any one time are oppositely disposed. The bridging member 51 in this case differs from that first shown and is like that in Fig. 5, in that the bolt opening or slot 52 therein is not cut through from the extreme edge of the member, as it is in the first form. This form of the invention is assembled substantially in the same way as previously described. In both Figs. 5 and 6 the bridging member on account of the closed character of

the slot or bolt opening therein has to be slipped over the end of the bolt or fixture supporting rod instead of being simply engaged laterally therewith as in the first form.

5 The form shown in Figs. 7 and 8 is similar to that just described in that the insert or body 60 is cylindrical in shape, but in this case the bridging member or support 61 is of full circular shape. To permit the insertion of this circular member up into the insert I have shown the supporting ledges 15 thereof as cut away at 62 at diametrically opposite points. These cuts are made wider than the thickness of the bridging member 15 or washer so as to allow the washer being pushed up therethrough, as indicated in dotted lines in Fig. 7. The washer is slotted at 63 to accommodate the bolt shank and it is evident that after being pushed up into 20 the chamber it will fall naturally beneath the upraised head of the bolt therein or may readily be moved to proper position. In the cylindrical forms of the insert body it will be noted that by turning the bridging member and sliding the bolt in the slot therein in the bolt can be set in any position in the opening 70 between the supporting ledges. These forms therefore are usually employed in situations where universal adjustment 25 may be necessary. The bridging member in these cylindrical forms of the invention, may be provided with a confining flange or flanges 71 similar to those first described.

The invention is readily installed and used, is simple and inexpensive to make and provides by its construction for all adjustments that may be necessary. And while the forms shown are the ones preferred at the present time I would have it understood 40 that other forms may be developed and modifications may be made without departing from the true spirit and scope of the invention.

What I claim is:—

45 1. A concrete insert comprising in combination a supporting bolt having a head at its upper end, a chambered anchorage member having oppositely disposed supporting ledges at the base of the chamber therein and spaced permanently apart a distance sufficient to admit the head of the supporting bolt and a one-piece unitary bridging member longer than the distance between said spaced ledges and insertible while 50 turned at an angle alongside the bolt shank up between the ledges into the chamber above the same into position beneath the upraised head of the supporting bolt within the chamber, whereupon said bridging member 55 may then be straightened out into position bridging the ledges and beneath the head of the supporting bolt, said bridging member having an elongated slot formed wholly therein extending transversely of 60 the supporting ledges and wide enough to

loosely receive the shank of the supporting bolt and adapted thereby to permit of the lateral movement of the one-piece bridging member necessary in engaging said one-piece bridging member beneath the upraised 70 head of the supporting bolt within the chamber and said chamber being of a height to receive the head of the bolt and the tilted bridging member beneath the same.

2. A concrete insert comprising a chambered anchorage member having longitudinally extending supporting ledges at the base of the chamber therein spaced apart in substantially parallel relation, a supporting bolt having a head on the upper end thereof of a size to pass up between said spaced apart ledges and a one-piece unitary bridging member of a length greater than the distance between said spaced apart longitudinally extending ledges and provided with an elongated slot therein extending transversely of the ledges and of a width to loosely receive the shank of the supporting bolt, whereby to permit of the engagement of the bolt shank in the slot in the bridging member and the tilting of the bridging member to an angular position wherein said bridging member will pass while tilted up between the supporting ledges into the chamber above the ledges and beneath the upraised head of the supporting bolt within the chamber and said chamber being of a height to receive the head of the bolt and the tilted bridging member beneath the same. 100

3. A concrete insert comprising in combination a supporting bolt having a head at its upper end, a chambered anchorage member having oppositely disposed supporting ledges at the base of the chamber therein and spaced permanently apart a distance sufficient to admit the head of the supporting bolt and a one-piece unitary bridging member longer than the distance between the spaced ledges and provided with an elongated slot therein as wide as the shank of the supporting bolt and extending from the central portion of the bridging member out through one end thereof to thereby permit of said bridging member being engaged sidewise over the shank of the bolt and inserted while tilted at an angle up alongside the bolt into the chamber past the ledges and beneath the upraised head of the bolt therein, said chamber being of a height to receive the head of the supporting bolt and the tilted bridging member beneath the same, whereupon the said one-piece bridging member may then be straightened out into position bridging the supporting ledges 115 and supporting the bolt aforesaid. 120

4. A concrete insert comprising in combination a supporting bolt having a head at its upper end, a chambered anchorage member having oppositely disposed supporting 130

ledges at the base of the chamber therein, spaced permanently apart a distance sufficient to admit the head of the bolt and provided with notched upper supporting faces and a one-piece unitary bridging member supported on said ledges and adjustable to different positions thereon, said one-piece bridging member having teeth on its under face engaging the notches in the upper faces of the ledges to anchor said one-piece bridging member in adjusted position on the ledges and being provided further with an

elongated slot formed wholly therein extending transversely of the supporting ledges and receiving the shank of the supporting bolt, said chamber being of a height sufficient to receive the head of the bolt and the tilted bridging member beneath the same. 15
